UNITED STATES PATENT OFFICE.

EMIL GUMBINNER, OF NEW YORK, N. Y.

DESIGN FOR A BELT-SLIDE.

SPECIFICATION forming part of Design No. 24,119, dated March 19, 1895.

Application filed January 29, 1895. Serial No. 536,604. Term of patent 7 years.

To all whom it may concern:

Be it known that I, EMIL GUMBINNER, a citizen of the United States, residing at New York, in the county and State of New York, have invented and produced a new and original Design for a Belt-Slide, of which the following is a specification.

The object of this design is to provide a handsome and ornamental belt slide which presents a characteristic and distinguishing appearance to the eye.

The design consists in an oblong body portion comprising a plurality of separated members, and having at one end a transverse, ornamental bar projecting laterally in opposite directions from the base of the oblong body.

The design is illustrated by the accompanying drawing, in which the figure is a perspective view of the belt-slide.

In the drawing the numerals 1, 3 and 4 indicate the longitudinal, separated members of the oblong body portion, and 2 the ornamental, transverse bar projecting laterally in opposite directions from the base of the oblong body. 25

The design provides an ornamental and handsome belt-slide.

What I claim, and desire to secure by Letters Patent, is—

The design for a belt slide, substantially as shown and described.

In testimony whereof I have hereunto set my hand in the presence of two subscribing witnesses.

EMIL GUMBINNER.
